(57) **CLAIM**

The ornamental design for a sandal, as shown and described.

DESCRIPTION

FIG. 1 is a front perspective view of a sandal;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depicting a region on the inner surface of the sandal in FIGS. 1–3 and 6–7 form no part of the claim. The broken lines depicting the sole on the bottom of the sandal in FIGS. 2–5 and 7 form no part of the claim. The broken lines depicting a region on the bottom side of the sandal in FIG. 7 form no part of the claim.

1 Claim, 7 Drawing Sheets
